[57] CLAIM

The ornamental design for a horse head hat, as shown and described.

DESCRIPTION

FIG. 1 is a front perspective view of the horse head hat showing my new design;

FIG. 2 is a rear perspective view of the horse head hat and illustrating my new design;

FIG. 3 is a bottom perspective view of the horse head hat of my new design; and,

FIG. 4 is a side perspective view of the horse head hat, the broken line showing of the human form is for illustrative purposes only and forms no part of the claimed design.
